US00D364114S

United States Patent

[19]

Weder et al.**Patent Number: Des. 364,114****Date of Patent: *** Nov. 14, 1995****[54] FLOWER POT COVER****[75] Inventors:** **Donald E. Weder; Joseph G. Straeter,**
both of Highland, Ill.**[73] Assignee:** **Highland Supply Corporation,**
Highland, Ill.**[*] Notice:** The portion of the term of this patent
subsequent to Apr. 2, 2005, has been
disclaimed.**[**] Term:** **14 Years****[21] Appl. No.:** **808,556****[22] Filed:** **Dec. 16, 1991****Related U.S. Application Data****[63]** Continuation-in-part of Ser. No. 710,272, Jun. 4, 1991,
abandoned, which is a continuation-in-part of Ser. No.
617,454, Nov. 21, 1990, abandoned, which is a continuation-
in-part of Ser. No. 411,249, Sep. 22, 1989, which is a
continuation-in-part of Ser. No. 411,247, Sep. 22, 1989,
which is a continuation-in-part of Ser. No. 411,245, Sep. 22,
1989.**[52] U.S. Cl.** **D11/164; D11/143****[58] Field of Search** **D11/143, 152,

Primary Examiner—Martie Thompson
Attorney, Agent, or Firm—Dunlap & Codding**[57]****CLAIM**The ornamental design for a flower pot cover, as shown and
described.**DESCRIPTION**FIG. 1 is a perspective view of our new flower pot cover
design;

FIG. 2 is a reduced side elevational view thereof;

FIG. 3 is a reduced top plan view thereof;

FIG. 4 is a reduced bottom plan view thereof;
FIG. 5 is a side elevational view of a second embodiment of
our new design; and,FIG. 6 is a side elevational view of a third embodiment of
our new design.

The flower pot cover has no substantial thickness.

The characteristic feature of the design resides in the specific
pleating arrangement comprised of the parallel disposition
of the exterior folds in combination with the interior
V-shaped folds all as best shown in FIG. 1.**1 Claim, 1 Drawing Sheet**## U.S. PATENT DOCUMENTS
